UNITED STATES PATENT OFFICE.

ALEXANDER C. MCCLURE, OF LOUISVILLE, KENTUCKY.

STEAM BOILER.

Application filed February 14, 1924. Serial No. 692,815.

To all whom it may concern:

Be it known that I, ALEXANDER C. MCCLURE, a citizen of the United States, residing at Louisville, in the county of Jefferson and State of Kentucky, have invented certain new and useful Improvements in Steam Boilers; and I do hereby declare the following to be a full, clear, and exact description of the invention, such as will enable others skilled in the art to which it appertains to make and use the same.

The invention has relation to boilers and more particularly to the type designed for generating steam and has for its object to replace the usual fire arch of refractory material by an arch which is hollow and through which the water is caused to circulate, said arch spanning the firebox and extending from near the lower end of the flue sheet backward towards the fire door, said arch being constructed of sheet or plate metal and strengthened by hollow stay bolts and connected to the side walls of the firebox in a manner to allow for contraction and expansion, the joint being fluted or corrugated so as to compensate for variation incident to extreme changes resulting from heating and cooling of the boiler.

Some of the objects of the invention may be briefly stated as follows, namely—a material increase in the direct heating surface of the firebox, an increase in the steaming capacity of the engine, a more positive and better circulation of the water, a material saving in the consumption of fuel, a material reduction in the stagnated points in the boiler, and the maintaining of a higher degree of temperature throughout the entire body of water in the boiler.

Another object of the invention is that, by providing additional, direct heating surface by means of the water arch, maintenance of full boiler pressure will be more easily accomplished, so that the draft may be modified by increasing the capacity of the exhaust nozzle tip regulating the draft on the fire and by so doing lessen impedance of the exhaust steam, or, in other words, provide for a less restricted discharge of the exhaust steam, and thereby lower the compression in the cylinders.

Other objects and advantages will be apparent and suggest themselves as the nature of the invention is understood.

While the drawings illustrate an embodi-

ment of the invention it is to be understood that in adapting the same to meet different conditions and requirements, various changes in the form, proportion and minor details of construction may be resorted to without departing from the spirit of the invention.

Referring to the accompanying drawings forming a part of the application:

Figure 1 is a vertical longitudinal section of the firing end of a steam boiler provided with a water arch within the firebox embodying the invention.

Figure 2 is a vertical transverse sectional view on the line 2—2 of Figure 1, looking in the direction of the arrows,

Figure 3 is a sectional view on the line 3—3 of Figure 1, looking in the direction of the arrows,

Figure 4 is an enlarged detail sectional view showing more clearly the stay bolt connection between the water arch and the outer wall or sheet of the boiler,

Figure 5 is a detail sectional view on the line 5—5 of Figure 4, looking to the left as indicated by the arrows,

Figure 6 is a detail sectional view showing the manner of connecting the upper ends of the water columns of the water arch to the crown sheet of the firebox,

Figure 7 is a similar view showing the manner of connecting the lower ends of the water columns to the water arch,

Figure 8 is a top plan view of the water arch assembly, and

Figure 9 a detail of one of the stay bolts.

Corresponding and like parts are referred to in the following description and designated in the several views of the drawings by like reference characters.

The steam boiler illustrated is of the horizontal flue type such as used in connection with locomotive engines, the firebox 1 being disposed at the inner or rear end. Within the lower forward portion of the firebox is located a water arch 2 which extends entirely across the firebox and which extends from near the lower end of the flue sheet upwardly and backwardly towards the fire-door 3. The water arch 2 thus spans the firebox and is connected at opposite sides to the inner walls or sheets of the firebox in a manner to compensate for contraction and expansion incident to extreme changes of temperature. The upper and lower sheets of the water arch are connected by hollow

stay bolts 4 and opposite edge portions are crimped or fluted, as indicated at 5, and are electrically welded or jointed in any preferred way to the side walls of the firebox. 5 Brackets 7 riveted or otherwise attached to the inner sides of the upper and lower walls of the water arch are connected by stay bolts 8 to the outer side walls of the firebox in a manner to compensate for contraction and 10 expansion. Nipples 10 are set into the walls 9 and the opening thereof is flared towards opposite ends, the outer flared end receiving a ball 11 provided at the outer end of each of the stay bolts 8 and the inner flared end of the opening providing for a pivotal movement of the stay bolt. A cap 12 closes the outer end of each of the nipples 10 and is 15 preferably threaded thereto, whereby provision is had for access to the stay bolt. 20 The upper rear end of the water arch 2 is connected to the crown sheet 14 of the firebox by means of water columns 13 and the end portions of the latter are outwardly flanged and crimped or corrugated, as shown 25 at 15, to allow for contraction and expansion, said flanged ends being welded or otherwise jointed to the crown sheet 14 and to the sheet forming a part of the water arch. Hollow stay bolts pass transversely through 30 the water columns and bracingly connect opposite portions thereof. Tubes 17 connect the lower forward end of the water arch to the lower portion of the flue sheet and the space thus formed between the lower end of the flue sheet 18 and the lower front end of the water arch may be closed by a tile 35 or fire brick 19, or may be left open thereby preventing ashes, cinders and the like from accumulating on the top of the water arch.

as well as by retarding the gases from the 40 fuel so that they are thoroughly ignited in the fire box, enabling the tubes 17 to function more effectively for heating the water. Suitable plugs 20 are provided for closing 45 openings in the outer sheets or walls of the boiler opposite the water arch and tubes 17, whereby these parts may be readily reached for cleaning.

The water arch, when installed, becomes a unit of the boiler itself and the corrugated 50 joints amply compensate for contraction and expansion and the peculiar connection of the stay bolts 8 with the outer walls provides in effect a ball and socket joint whereby said stay bolts may move with the water arch 55 when contracting and expanding without tending to break joint at their outer ends with the outer walls of the boiler.

What is claimed is:

In a steam boiler, a hollow arch located 60 in the rear portion of the fire box and inclined downwardly towards the rear wall thereof, said arch being made of sheet metal and having open ends secured to the inner walls of the opposite sides of the fire box, 65 said open ends having outwardly directed integral flanges secured to said inner walls by welding, the flanges being fluted to provide compensation for contraction and expansion of the boiler plates, the lower end of said arch being spaced from the flue sheet 70 at the rear of the fire box, tubes connecting the flue sheet and said lower end of the arch, and water columns connecting the upper end of the arch and the crown sheet. 75

In testimony whereof I affix my signature.

ALEXANDER C. MCCLURE.
